PNEUMATIC PLAY PEN

Shoji Suzuki, 6-11, 3-chome, Higashi-Mukojima,
Sumida-ku, Tokyo, Japan

Filed Apr. 6, 1972, Ser. No. 241,888

Claims priority, application Japan Jan. 27, 1972

Term of patent 14 years

Int. Cl. D6—06

U.S. Cl. D6—13

FIG. 1

FIG. 2

FIG. 3

FIG. 1 is a top perspective view of a pneumatic play pen showing my new design with a bottom section thereof broken away to show the level of the floor of the pen; and

FIG. 2 is a top plan view thereof.

FIG. 3 is a bottom plan view thereof.

I claim:

The ornamental design for a pneumatic play pen, substantially as shown and described.
